FRED W. GLAHE, OF CHICAGO, ILLINOIS, ASSIGNOR TO CHARLES E. DORAIIS, OF DETROIT,
MICHIGAN

ATHLETIC TROUSERS

Application filed February 12, 1931. Serial No. 515,163.

This invention has to do with improvements in an athletic garment and particularly to improved constructions designed to permit freedom of movement of a joint such as the knee or elbow. The invention is particularly concerned with such a construction at the knee of athletic trousers and is exemplified in trousers used in the game of football. The invention embodies a construction employing an excess of material to permit of knee movement such as is described and claimed in the patent application of Charles E. Dorais, filed June 27, 1929, Serial No. 374,067, and involves different arrangements of the goods and parts which go to make up the trousers.

In the accompanying drawings:

Fig. 1 is a front view illustrating that portion of a trousers leg at about the knee of the wearer.

Fig. 2 is a section taken substantially on line 2—2 of Fig. 1.

Fig. 3 is another section illustrating the trousers leg as it may appear when the knee is bent.

Fig. 4 is a front view of the modified form of trousers leg structure.

Fig. 5 is a section taken substantially on Fig. 5—5 thereof.

Fig. 6 is a section showing the structure of Fig. 5 when the knee is bent.

Fig. 7 is a view showing trousers such as may be employed with the knee structures shown in Figs. 1, 2 and 3.

The trousers comprises a suitable trunk portion 1 and main leg portions 2, with terminating leg portions 3 designed to terminate a distance below the knee. As shown in Fig. 2 the material at the back of the leg may be continuous; in other words, a single piece of material may extend down the back of the main leg portion 2 to the lower edge of the terminating leg portion. The front part of the leg may be a separate piece or pieces of material, with the front and back connected by a seam at the side, as shown at 4. An elastic 5 may be employed at the lower edge of the leg and advantageously it may be used only at the lower edge of the back piece 6, and preferably it is confined in a hem or the like

as shown. Thus the lower part of the leg is designed to relatively snugly fit the leg of the wearer to form a close fit preferably with no substantial flapping or looseness.

To permit of knee movement, however, sufficient excess material is provided, and this is arranged to be confined when the knee is substantially straight so as to present a trim, snug appearance. The material at the front of the leg, at about the knee, is folded back as at 10 so as to extend upwardly, and then folded again upon itself as at 11. This fold is at about the knee and is designed to be normally concealed when the leg is straight as shown in Fig. 2. For this purpose padding and stiffening elements for protecting the knee may be utilized. In the main leg portion, which I will term that portion just above the fold, there is preferably placed a relatively stiff insert which may be of fiber board or the like, shown at 12, and it may be held in place and enclosed by a covering piece 13 sewed to the inside of the leg. Just below the fold or in the terminating leg portion there may be another fiber or relatively stiff protecting insert 14, and over it may be a padding of felt or the like 15. These may be secured by stitches 16 and 17 taken both through the padding and insert. The stiff insert may extend well up toward the reverse fold 11. The lower edge of the front part of the leg may be suitably reinforced by the hem, as at 18. The folded material may be stitched together at the side seams 4, and at the front stitched or otherwise secured for a slight distance in towards the center line, and reinforced by stitches or leather pieces 19. Between the parts 19 there is no connection, as shown in Fig. 2, save for the indirect connection through the folded parts. When the leg is bent the terminating portion, including padding 15 and reinforcement member 14, follow with that part of the leg below the knee and draws away from the main leg portion which is permitted by the pulling out of excess material. This is illustrated in Fig. 3 showing substantially the limit of movement. Due to the arrangement and construction of parts the fold is at all times, when the leg is normally straight, held con-

cealed so that there is no excess material visible in the nature of folds or the like, thus presenting a clean cut snug appearance which also works to material advantage in the game of football as it minimizes the possibility of opposing players catching hold of excess or loose cloth. When the leg is straightened the parts 14 and 15, being of relatively stiff formation, effectively carry the fold 11 back in behind the lower edge of the main leg portion. More specifically, behind the parts identified by the characters 12 and 13.

A modified form is shown in Fig. 5. Here the cloth forming the front of the trouser, as shown at 20, is folded back as at 21, folded again upon itself as at 22, provided with another fold upon itself 23 and then turns down as at 24, to form the terminating part of the knee. This leaves a gap as shown; while the material at 25 remains visible this is the same material as forms the other parts of the front of the trouser. A suitable stiff reinforcement element, such as fiber or the like as at 26, padded by element 27 may be positioned at 25 the lower edge of the main leg portion, while a similar reinforcing element 28 and pad 29 may be used at the upper part of the terminating leg portion; to the rear of the part 25 there may be a stiffening element 30 padded by pad 31. The rear part of the trouser leg, as shown in Figs. 4, 5 and 6 may be substantially the same as that shown in Fig. 2. When the leg is bent the excess material is drawn out as illustrated in Fig. 6. In this form the stiff reinforcement members substantially overlap and at all times substantially protect the knee.

When it is said herein that excess material is distended it is not meant that the same is drawn taut, as many times the knee may be bent only partially. Maximum bending of the knee may not draw the excess material taut.

Claims:

45 1. An athletic trouser comprising a leg portion positioned in the main above the knee, a portion below the knee, the cloth forming the front of the leg extending from the first mentioned portion to the lower edge 50 of the second portion and being folded back upon itself to extend upwardly, and then again upon itself to extend downwardly to form a fold of excess material, reinforcement means positioned in the first portion and extending substantially to the first fold, and reinforcement means in the second portion arranged to slightly overlap the first reinforcement means when the leg is straight, the material of the fold between said portions adapted to be distended when the knee is bent.

60 2. In an athletic trouser leg, a piece of fabric at the front of the leg folded back upon itself substantially at the knee, said fabric being again folded upon itself to ex-

tend downwardly to form a lower end of the trouser below the knee, reinforcement means positioned with the part substantially in the first fold, and reinforcement means inside the trouser leg and secured to the said fabric substantially at the second mentioned fold. 70

3. In an athletic trouser, a main leg portion and a terminating leg portion of fabric or the like for disposition on opposite sides 75 of the knee of the wearer, said terminating leg portion being arranged to snugly fit the leg of the wearer below the knee, a stiff reinforcement member attached to the fabric of the front of the main leg portion, said member defining the lower edge of the main leg portion, said fabric being folded upwardly 80 around the lower edge of the said member, and then being folded upon itself and extending downwardly to form the terminating leg portion, a reinforcement member inside the fabric of the terminating leg portion and secured thereto substantially at the second fold above the lower edge of the first 85 mentioned reinforcement member.

4. In an athletic trouser, a main leg portion and a terminating leg portion of fabric or the like for disposition on opposite sides of the knee of the wearer, said terminating leg portion being arranged to snugly fit the 90 leg of the wearer below the knee, a stiff reinforcement member attached to the fabric of the front of the leg portion, said member defining the lower edge of the main leg portion, said fabric being folded upwardly around 95 the lower edge of the said member, and then being folded upon itself and extending downwardly to form the terminating leg portion, a reinforcement member inside the fabric of the terminating leg portion and secured thereto substantially at the second fold above the lower edge of the first 100 mentioned reinforcement member, and a pad member secured to the inside of the second reinforcement member. 105

5. In an athletic trouser, a main leg portion and a terminating leg portion of fabric or the like for disposition on opposite sides of the knee of the wearer, said terminating leg portion being arranged to snugly fit the 110 leg of the wearer below the knee, a stiff reinforcement member attached to the fabric at the front of the leg portion, said member defining the lower edge of the main leg portion, said fabric being folded upwardly 115 around the lower edge of said member, and then being folded upon itself and extending downwardly to form the terminating leg portion, a reinforcement member inside the fabric of the terminating leg portion and secured thereto substantially at the second fold 120 above the lower edge of the first mentioned reinforcement member, a pad member secured to the inside of the second reinforcement member, said pad member extending 125 130

upwardly beyond the second fold in the fabric.

6. In an athletic trouser, a back fabric forming the back of the trouser leg and extending to the bottom of the trouser leg below the knee of the wearer, a front fabric member extending beyond the knee of the wearer to the bottom of the trouser, said trouser at the bottom being designed to relatively snugly fit the leg of the wearer, the front fabric being folded upwardly and then downwardly to provide excess material, reinforcement means secured to the fabric in the first fold, and reinforcement means secured 10 to the fabric inside the part of the fabric which extends downwardly from the second mentioned fold.

7. In an athletic garment, a main leg portion and a terminating leg portion positioned 20 on opposite sides of the knee of the wearer, the fabric at the front of the leg at substantially the knee being folded inwardly and upwardly, then folded again downwardly, then again folded upwardly, and having a fourth fold downwardly, the first and last folds defining the lower and upper edges, respectively, of the main leg portion and terminating leg portion, the material in the folds being adapted to be distended when the leg is bent.

8. In an athletic garment, a main leg portion and a terminating leg portion positioned on opposite sides of the knee of the wearer, the fabric at the front of the leg at substantially the knee being folded inwardly and 35 upwardly, then folded again downwardly, then again folded upwardly, and having a fourth fold downwardly, the first and last folds defining the lower and upper edges, respectively, of the main leg portion and terminating leg portion, the material in the folds being adapted to be distended when the leg is bent, reinforcement means substantially in the first fold, and reinforcement means substantially in the fourth fold for 40 defining said upper and lower edges, respectively.

9. In an athletic garment, a main leg portion and a terminating leg portion positioned on opposite sides of the knee of the wearer, the fabric at the front of the leg at substantially the knee being folded inwardly and upwardly, then folded again downwardly, then again folded upwardly, and folded a 45 fourth time downwardly, the first and last folds defining the lower and upper edges, respectively, of the main leg portion and terminating leg portion, the material in the folds being adapted to be distended when the leg is bent, reinforcement means substantially in the first fold, reinforcement means substantially in the fourth fold for defining said upper and lower edges, respectively, and a reinforcement means attached to said fabric inside the leg and between the second and 55 third mentioned folds.

10. In an athletic trouser, a front fabric having a fold upwardly to define the lower edge of a main leg portion, reinforcement means in the fold, said fabric being folded a second time downwardly, and a third time upwardly, reinforcement means between the second and third folds and inside the trouser, said fabric then having a downward fold defining the upper edge of a terminating leg portion, reinforcement means in the last mentioned fold, the said lower and upper edges of the leg portions being normally spaced with the fabric material between the second and third folds positioned interiorly thereof and bridging said space. 70

11. In an athletic trouser, a front fabric having a fold upwardly to define the lower edge of a main leg portion, reinforcement means in the fold, said fabric being folded a second time downwardly, and a third time upwardly, reinforcement means between the second and third folds and inside the trouser, said fabric then having a downward fold defining the upper edge of a terminating leg portion, reinforcement means in the last mentioned fold, the said lower and upper edges of the leg portions being normally spaced with the fabric material between the second and third folds positioned interiorly thereof and bridging said space, and a pad covering the reinforcement on the portion between the second and third folds. 75

12. In an athletic trouser, a front fabric having a fold upwardly to define the lower edge of a main leg portion, reinforcement means in the fold, said fabric being folded a second time downwardly, and a third time upwardly, reinforcement means between the second and third folds and inside the trouser, said fabric then having a downward fold defining the upper edge of a terminating leg portion, reinforcement means in the last mentioned fold, the said lower and upper edges of the leg portions being normally spaced with the fabric material between the second and third folds positioned interiorly thereof and bridging said space, and pads over each of the three reinforcement means. 80

In testimony whereof I affix my signature.
